UNITED STATES PATENT OFFICE.

CLARENCE ALBERT HACH, OF OAK PARK, ILLINOIS, ASSIGNOR TO WESTERN ELECTRIC COMPANY, INCORPORATED, OF NEW YORK, N. Y., A CORPORATION OF NEW YORK.

METHOD OF AND APPARATUS FOR ELECTROPLATING.

1,280,213.

Specification of Letters Patent.

Patented Oct. 1, 1918.

Application filed January 12, 1917. Serial No. 141,935.

To all whom it may concern:

Be it known that I, CLARENCE ALBERT HACH, a citizen of the United States, residing at Oak Park, in the county of Cook and 5 State of Illinois, have invented certain new and useful Improvements in Methods of and Apparatus for Electroplating, of which the following is a full, clear, concise, and exact description.

10 This invention relates to an improved method of and apparatus for electro-plating, and more particularly to a method of and apparatus for increasing the speed and efficiency with which the plating operation can 15 be performed.

In electro-plating operations as practised commercially very small hydrogen bubbles are continuously evolved at the cathode or article to be plated, said bubbles having a 20 tendency to adhere to the surface of the article. These hydrogen bubbles prevent contact between the plating solution and the surface of the article which is being plated, which interferes with the plating process at 25 the point of contact and frequently results in the formation of pits in the plated coating.

This invention contemplates an improved method of and apparatus for rapidly removing 30 said hydrogen bubbles, which makes it possible to use higher current densities and thereby to increase the speed of plating without pitting. In the preferred form of the invention herein illustrated and described 35 these hydrogen bubbles are carried away by air liberated in the form of small bubbles directly under the article that is being plated, said air bubbles constituting a continuous stream, which bombard the surface of the article and carry with them as they rise to the surface of the plating solution the hydrogen bubbles which are being generated at the surface 40 of the article and tend to adhere to said surface. The bubbling of air through the plating solution also serves to agitate said solution, which action also makes it possible to increase 45 the speed of plating. The process of air agitation for the purpose of producing circulation for plating solutions is old, and this result is obtained merely as an incident 50 in the application of this new process, which seeks primarily to remove the hydrogen bubbles by air agitation and which also accomplishes secondarily the circulation of the 55 plating solution. While the process of re-

moving the hydrogen bubbles by a bombardment of air bubbles is beneficial and applicable to practically all electro-plating processes, it is especially applicable to the plating process in which the anodes are shaped to conform to the contour of the article that is being plated. In this case the air supply can be readily located in the special shaped anode, so that the entire surface of the article that is being plated will be treated to a 60 65 continuous stream of bombarding air bubbles.

The invention is illustrated in the accompanying drawings in which:

Figure 1 shows a plan elevation of the 70 plating tank with the anode and cathode and their associated apparatus in proper position;

Fig. 2 is a vertical section on the plane 2-2 of Fig. 1 looking in the direction of the 75 arrows, and

Fig. 3 is a vertical section of an anode on the plane 3-3 of Fig. 1 looking in the direction of the arrows.

The apparatus is all mounted in the plating tank or receptacle 10 which carries a suitable plating solution. In the bottom of said tank, as illustrated in Fig. 2, is a heating steam coil 11 having an inlet at 12 and an outlet at 13 which is utilized to heat the 80 85 plating solution and keep it at a temperature at which the plating operation can be most satisfactorily performed. Directly above the heating coil 11 is a second coil 14 which is equipped with a series of perforations and which is connected at 15 to an air supply lead which furnishes compressed air to the coil. The compressed air supplied to the coil escapes through the perforations and through the plating solution out into the atmosphere of the room. This escaping air 90 functions to produce a circulation of the plating solution in the tank, and since the coil is placed at substantially the lowest portion of the tank, the escaping air will produce practically the same amount of agitation throughout the entire volume of the tank. Mounted near the upper portion of the tank are two brackets or shelves 16 and 17 which serve as supports for the anodes such as 20. These anodes may be of any desired shape or form, but are preferably made so as to conform substantially to the shape of the article to be plated. In the preferred embodiment of the invention here- 100 105 110

in illustrated the articles to be plated such as 19 have a somewhat irregular shape which accentuates the special shape of the anode 20, as clearly illustrated in Fig. 3. The various 5 anodes 20 are mounted in perforations in the shelves 16 and 17 and are each equipped with a plurality of perforations such as 21 which facilitate the proper circulation of the plating solution from the exterior of the 10 anode into and through the interior of the anode and back into the solution outside of the anode.

Mounted directly beneath each of the shelves 16 and 17 is a pipe such as 22 which 15 is connected to a compressed air supply line. Rising from this pipe 22 directly beneath each anode is a riser such as 23, 24, and 25, above which is mounted some inert porous material 26, preferably "filtros" or some 20 other porous stoneware, or any perforated material inert to the solution used, as clearly illustrated in Fig. 3. The anode 20 is supplied with an opening directly above the "filtros" 26 which has an area substantially 25 equal to the area of the "filtros". The "filtros" 26 may be connected either directly to this opening or may be separated therefrom very slightly, as indicated in Fig. 3, so as to permit circulation of the plating solution 30 through this lower opening in the anode.

The article 19 to be plated is secured to a lug 27 depending from a rod such as 28 by any suitable means which will permit speedy and efficient attachment and removal of the 35 article from said lug. The lugs 27 are connected to the rods 28 having a relatively high electrical conductivity, preferably copper, and these rods are in turn connected to a frame 29. Each end of the sides of this 40 frame is given a slight upward inclination, as shown in Fig. 2, and these ends of the frame constitute handles whereby the frame and the attached rods and cathodes or articles to be plated can be readily removed 45 from the plating tank. When the articles to be plated or cathodes are lowered into the plating solution and the various anodes 20 for plating, the rods 28 associated with the cathodes or articles to be plated will rest 50 on the copper frame 30 which is mounted on the top of the tank 10 by means of the insulating blocks 31, 32, 33, and 34. Attached to the copper frame 30 is the terminal lug 35 which is connected to one terminal of the 55 electrical circuit which supplies the plating current. Extending completely across the middle portion of the tank is the copper rod 36 to which the various anodes are connected by means of the copper bars 37, 38, 39, and 60 40, the copper rod 36 being connected to the other termination of the circuit which supplies the plating current.

When a plurality of articles such as 19 to be plated have been lowered into the various 65 anodes 20 by means of the frame 29,

and the current is connected to the frame 30 and the rod 36, the current will flow from the anode through the plating solution in the anodes to the articles 19 to be plated and back to the other terminal of the circuit by 70 way of the rod 36. This will start the metal depositing action from the plating solution onto the articles to be plated, and this action will be accompanied by the generation of very small bubbles of hydrogen on the surfaces of 75 the articles that are being plated. As long as these bubbles are very small they have a tendency to cling to the surface of the article, and such bubbles prevent contact between the plating solution and the surface 80 of the article and little or no metal will be deposited on the article at the place of contact between the article and the bubble until the bubble is removed. To remove these hydrogen bubbles, the compressed air in the 85 pipe 22 continuously filters through the "filtros" located between the lower opening in each anode. The air is filtered through the "filtros" in such a way that the resulting bubbles rising therefrom are very minute in size 90 and likewise very great in number. These air bubbles rapidly rise through the plating solution contained in the anode and strike the surface of the article which is being plated. In this manner the compressed air from the 95 pipe line 22 is released in a continuous flow 100 of bubbles under each article which is being plated, said air bubbles bombarding the surface of the article that is being plated and carrying with them the hydrogen bubbles that are being generated on the surface of the article, due to the plating operation. This continuous bombardment of air bubbles keeps the surface of the articles which are being plated substantially clear 105 of hydrogen bubbles, permits a greater speed 110 in the plating operation, and prevents the forming of pits in the plated surface. The air bubbles rising through the solution contained in the anode also function to circulate this solution and draw fresh solution from the tank through the openings in the lower part of the anode, so that the solution within the anode will always be rich in metal content which is necessary for speedy, 115 efficient, and satisfactory plating. The use of the compressed air means for the removing of hydrogen bubbles in the process of plating consequently results in a speedier 120 and more efficient plating process and also in 125 a much more satisfactory product.

Obviously the invention is not limited to the specific embodiment herein shown and described, but is capable of many variations and applications without departing from its spirit and scope, as set forth in the appended claims.

What is claimed is:

1. An improved process of plating which consists in automatically removing the bub- 130

- bles of hydrogen as they are generated on the surface of the cathode during the plating operation by a continuous stream of bombarding gas bubbles, said bubbles being maintained minute in size by filtration through an inert porous material whereby said bubbles are uniformly distributed to impinge against the entire surface of said cathode which is to be plated.
2. In a device for plating articles, the combination with a solution containing receptacle, a cathode, an anode, a source of current supply connected to said cathode and said anode, pneumatic means comprising a constant stream of gas which generates bubbles to remove the hydrogen bubbles generated on the article connected to said cathode during the plating operation, and an inert porous material through which
- said gas is filtered prior to the formation of said bubbles.
3. In a device of the character described, the combination with a solution containing receptacle, of a cathode, an anode shaped to conform substantially to the shape of the cathode, a source of current connected to said cathode and said anode, pneumatic means comprising a constant stream of gas operated to remove hydrogen bubbles generated on the cathode during the plating operation, and a filter comprising an inert porous material located beneath the cathode through which said gas is forced before reaching said cathode.

In witness whereof, I hereunto subscribe my name this 29th day of Dec., A. D. 1916.

CLARENCE ALBERT HACH.
